DESIGN FOR BACKS OF PLAYING-CARDS.

Design No. 10,246, dated September 11, 1877

UNITED STATES PATENT OFFICE.

ALFRED J. MANNING, OF NEW YORK, N. Y., ASSIGNOR TO ANDREW DOUGHERTY, OF SAME PLACE.

DESIGN FOR BACKS OF PLAYING-CARDS.

Specification forming part of Design No. 10,246, dated September 11, 1877; application filed August 4, 1877.
[Term of Patent 7 years.]

To all whom it may concern:

Be it known that I, ALFRED J. MANNING, of the city, county, and State of New York, have invented and produced a new Design for the Backs of Playing-Cards, of which the following is the specification:

A is the central panel, and B a surrounding border, composed of oval figures a. A waved vine, b, ornamented by leaves t, running through said figures, is inclosed within border-lines c' c''.

In the center of the panel is a rosette, C, forming the center of a dark cross, d, inclosed by a border, e.

A ribbon, i, forming a continuation of the border c', runs through the panel, as shown, and at the corners of panel are lattice-like corner-pieces h.

I claim—

1. The design for the back of a playing-card, consisting of a panel containing the cross d, rosette C, and ribbon i, as specified and shown.

2. The design for the back of a playing-card, consisting of a center-piece having the panel d, substantially as shown and described.

3. The design for the back of a playing-card, consisting of a border having the oval figures a and vine b, as specified and shown.

4. The design for the back of a playing-card, consisting of the panel composed of the rosette C, cross d, ribbon i, and corner-pieces h, as shown and described.

5. The design for the back of a playing-card, consisting of the waved border-line b and its leaves t, substantially as shown and described.

In testimony whereof I have signed my name to this specification in the presence of two subscribing witnesses.

ALFRED J. MANNING.
